PROTECTIVE CASING FOR TEXTILES BY THE YARD

William Polgar, New York, N. Y.

Application August 31, 1944, Serial No. 552,075

7 Claims. (Cl. 242—55.2)

This invention relates to the art of storing fabrics consisting of various materials, and has particular reference to improvements in the storing of textile fabrics to protect the same against fire, smoke, dust and other injurious elements.

Accordingly, one object of the invention is to provide an improved safety container which is fireproof, smokeproof and dustproof, and is adapted for housing textile fabrics by the yard, stored therein compactly so that the fabric may be easily withdrawn and returned into the container as by means of a rotating shaft or in any other suitable manner.

Another object of the invention is the provision of a device of the type mentioned having few and simple parts, adapted to be manufactured and assembled in an inexpensive manner in quantity production, and which is durable, convenient, reliable and efficient to a high degree in use, compact and neat in appearance, easy to install, and which will remedy various drawbacks now existent in the handling of textiles by the yard in retail establishments, as well as in wholesale houses.

It is well known that according to the present practice of selling textiles by the yard, it is customary to show the buyer different colors, patterns, styles and qualities by removing rolls of textile fabrics from shelves and unrolling substantial portions of the goods sufficient to afford a good exhibit or drape whereby the buyer can clearly visualize the effect of the goods when applied for its intended use. The result is that often a large number of partially open rolls are piled on tables or counters. Hence considerable space is consumed and confusion occurs, and much work is entailed in again rolling up the goods and returning the rolls to their specified places on the shelves. Often the goods are thus subjected to damage, and in general the number of buyers that can be handled is substantially reduced.

The instant invention aims to greatly reduce the time and labor thus involved, assure convenience in the showing of large fabrics, and avoid the possibilities of damage thereto.

Another object of the invention is to provide a device having the advantages noted, in conjunction with improvements whereby the textile fabric is housed for safety against fire, smoke, dust and the like.

More particularly, the safety of the fabric is assured by the provision of an improved container made of metal or other fire resistant ma-

terial with closure means of a novel character to facilitate the showing of textile fabric and the closing of the container for the safety of the goods; a series of such containers being mounted in a frame in superposed relation to each other, each container having a rotatable shaft for a different textile fabric whereby a large number of fabrics can be shown the customer by unrolling the textiles and then protectively enclosed by merely rotating the shafts, without requiring removal of the shafts from the containers or removal of the latter from the frame, although of course the textiles in the containers may be easily replaced by others of a different pattern if desired.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a diagrammatic view in front elevation with parts removed showing a device embodying the invention, and indicating different depending fabric portions.

Fig. 2 is a view in side elevation thereof.

Fig. 3 is an enlarged view of a container for a textile fabric, exemplifying one of the elements of Figs. 1 and 2, according to an embodiment of the invention.

Fig. 4 is a sectional view thereof taken on line 4—4 of Fig. 3.

Fig. 5 is a view like that of Fig. 4 but showing an opening position of the container.

The advantages of the invention as here outlined are best realized when all of its features and instrumentalities are combined, but, useful embodiments may be produced involving less than the whole.

It will be obvious to those skilled in the art to which the invention appertains, that the same may be incorporated in several different constructions. The accompanying drawings, therefore, are submitted merely as showing a preferred exemplification of the invention.

Referring in detail to the drawings, 10 denotes a device embodying the invention. The same may comprise a frame having one or more vertical sections such as 11, each section being of rectangu-

lar form with top and bottom walls 12, 13 and side walls 14, 15. These sections 11 may be interconnected into a single frame by top and bottom walls 16, 17. The frame shown is only illustrative, and may be replaced by any other that will suit. It is open at opposite sides to expose safety container devices 18 for textile fabrics more particularly shown and described hereinafter. For compactness, each section may have one or two upright rows of the containers 18 as shown in Fig. 2, these being equally vertically spaced and being mounted by fitting their end portions in openings 19 in the walls 14, 15. The containers 18 are normally stationary, but they may be removably or permanently engaged with the said walls in any suitable manner at the openings 19. As will be more clearly apparent hereinafter, the rows of container devices may be vertical or at an upwardly diverging angle as may best suit the handling of the textile fabrics in a series of the containers simultaneously, and so that each upper sheet of fabric shall lie a little forwardly of the next lower fabric and avoid rubbing between the fabrics.

It will be noted that the container devices 18 of Fig. 1 are shown in open position except for one at the top of the right hand column which is shown closed for illustration. Sections of textile fabrics 20 are shown withdrawn so as to depend from their respective container devices 18, the different colors, patterns, etc. being diagrammatically illustrated by different cross hatching. Accordingly, the buyer can observe numerous fabrics at a glance; such fabrics need not be removed from the container devices, but may be unrolled to show a larger piece of it if necessary.

Referring now more particularly to Figs. 3, 4 and 5, the container devices 18 are made of metal so as to afford fireproof, smokeproof and dust-proof protection for the fabrics. They may also be made of any other fire resisting material. Each device 18 comprises a generally cylindrical casing 21 which is horizontal and is formed with a bottom opening 22 less than the length of the casing in order to provide annularly continuous end portions 23 adapted to fit in the openings 19 of the supporting frame. The end walls 24 of the casing are formed with central holes 25 constituting bearings for a shaft or roller 26, the same being removably retained in the casing by any suitable elements 27 removably connected to the shaft to prevent endwise movement thereof while permitting it to have freedom of rotation. Secured axially to one end of the shaft, as by a screw thread, is a handle 28 whereby the shaft can be turned. To this shaft 26 the fabric 20 is preferably connected at its inner end in any suitable manner so that the fabric can be rolled and unrolled on the shaft without becoming accidentally detached, especially where the length of the fabric has become comparatively small. In any well known manner, the fabric can be attached directly to the shaft or by means of an intermediate piece of sheet material that is permanently secured to the shaft.

From the casing 21, along the longitudinal edges of the opening 22, there are the relatively fixed or stationary walls 29, 30 which may be integral with the casing. Of these, the rear wall 29 is of considerable vertical length, while the front wall 30 is much shorter and is downwardly inclined toward the rear wall; but both walls are of the same horizontal dimension. Hingedly connected at 31 to the wall 30 is a panel 32, and hingedly connected to the latter at 33 is a panel 34. The

elements 30, 32 and 34 may be considered as forming a generally flexible wall of about the same length as the wall 29, and may be marginally flanged to engage the wall 29 in the manner of a box-like structure. However, it suffices to provide side flanges 35 on the panel 32 and side flanges 36 as well as a bottom flange 37 on the panel 34. The flanges referred to are so arranged and shaped as to be adapted to receive and frictionally engage the adjacent portion of the wall 29 to thus form an enclosure for the section of the fabric 20 that depends from the casing device 18. The space between walls 30 and 29 may be regarded as substantially closed by the closely adjacent frame walls 14, 15. A locking device may be provided to releasably interconnect the elements 29 and 34 to retain them in closed engagement. The depending fabric section is instantly visible upon swinging the panel 34 upwardly as shown in Fig. 5 and at the upper left in Fig. 1. To thus retain the panel 34, any suitable releasable locking device may consist, for instance, of a hook 38 connected to the casing 21 and being engageable with an eye 39 on the panel 34. If it be desired to swing upward and thus hold both panels 32, 34, in the manner of the latter, then a similar device may comprise a hook 40 connected to the casing 21 and engageable with an eye 41 on the panel 32, the hinges 33 having a limited range of angular motion to retain the panel 34 in upward extending position. In this manner access is readily had to the interior of the casing 21 as for attaching the fabric 20 to the shaft. It will now be apparent that the container device 18 especially in association with suitable frame sections as in Fig. 1 constitutes a protective container for the fabric and permits instant showing of the fabric.

The device 10 is especially adapted to be built in different sizes, and it may be built as high as desired, and can be used to show fabrics at opposite sides. Similarly, the containers may be made in different sizes according to the dimensions of the roll of cloth. For containers which are spaced rather high, belts or other devices within easy reach may be provided to rotate the shafts 26. Any number of the containers may be mounted in a frame, each row having as many of the containers as desired.

It will be understood that the different containers may be given consecutive or other serial numbers, or may have the stock or style numbers of the fabrics applied thereto or to the adjacent parts of the frame. Various other legends, trademarks, etc., may be used for easy identification of the goods, and prices and other data may also be applied, as "washable," "gingham," "velvet," "plush," "linen," "silk," and so on. And it will be appreciated that while the metallic structure of the device may increase the cost thereof, the cost of fire insurance will be diminished.

The invention thus provides a novel, improved means for the instantaneous showing and for the convenient handling and selling of textile fabrics by the yard, it being merely necessary to open the panels 34. If the customer is interested in a certain fabric, the same is further unrolled, inspected, and a section thereof sold; or the portion so unrolled may be wound back on its shaft by turning the corresponding handle 28. Before the store is locked up for the night, it is merely necessary to close the panels 34 to protect the fabric against fire, smoke and dust. At all times, all the rolls of cloth are in their respective places, properly marked for instantaneous identification.

Nothing can be mislaid. The confused condition of piles of heavy rolls of cloth is avoided, the time and labor in moving the same to and from shelves and the danger of damaging the goods are all avoided. Each salesman can handle more customers and do so in a much more efficient and business-like manner than heretofore. The containers 18 are of such length as to receive a related series of different widths of textiles; for example, if intended for 36 inch fabric, the containers are preferably made 40 inches internally to be adapted to also receive 38 and 40 inch fabrics. Thus the containers may be said to be capable of receiving textiles of related graduated widths, which affords a substantial advantage.

I claim:

1. A device for protectively housing textile fabrics, including an elongated horizontal casing having an opening along the bottom thereof, a shaft adapted to carry a roll of fabric, said casing having end bearings for mounting said shaft, a handle external of the casing connected to said shaft for rotating the latter to wind and unwind said fabric, said shaft being so related to said opening that an unwound portion of the fabric is adapted to depend through said opening, and opposed walls parallel to and connected to said casing along the edges of said opening, said walls depending downward and being adapted to house therebetween a portion of the fabric projecting from said opening, one of said walls comprising a portion upwardly movable to expose said depending fabric portion.

2. A device according to claim 1 including marginal flanges along one of said walls engageable with the other wall to provide an enclosure for a depending fabric portion.

3. A device according to claim 1, including means for releasably locking the said movable wall portion in its upward position.

4. A device according to claim 1 wherein the said movable wall portion is upwardly movable to different elevations one of which is sufficiently high to expose said opening for convenient

access into the casing, and different locking means are provided to releasably support the movable wall portion at said different elevations.

5. A device for protectively housing a fabric sample, including a generally cylindrical horizontal casing, the latter having end bearings therein for rotatably mounting a shaft for winding and unwinding said fabric, said casing having a longitudinal bottom opening, a relatively narrow chute-like means comprising walls connected to the casing at opposite edges of said opening so that said walls depend therefrom to house a depending portion of the fabric, one of said walls being fixed, the other wall having 10 hingedly interconnected horizontal panels swingable upwardly and away from the companion wall to open position, one of the panels having marginal flanges releasably engageable with the companion wall to form an enclosure for the depending portion of the fabric when the panels are in depending position, and supporting means for releasably causing one or more of the panels to be supported at will in said open position.

6. A device for protectively housing a continuous roll of fabric to be sold by the yard, including an elongated horizontal casing having a longitudinal opening along the bottom thereof, a shaft to carry said roll of fabric, said shaft being journaled on the casing, said shaft being so related to said opening that an unwound portion of the fabric is adapted to depend for inspection through said opening, and opposed walls parallel to and connected to said casing along the edges of said opening, said walls depending downwardly and being adapted to house therebetween said depending portion of the fabric, one of said walls having a longitudinal portion movable to expose the depending fabric portion.

7. A device according to claim 6 including means for mounting the movable longitudinal portion in the different positions mentioned to cover the fabric or to expose the same.

WILLIAM POLGAR.
